UNITED STATES PATENT OFFICE.

ERNEST E. SWEET, OF DETROIT, MICHIGAN.

TAIL-LIGHT FOR VEHICLES.

1,097,737.

Specification of Letters Patent. Patented May 26, 1914.

Application filed March 10, 1913. Serial No. 753,187.

To all whom it may concern:

Be it known that I, ERNEST E. SWEET, a citizen of the United States, and a resident of Detroit, in the county of Wayne and State of Michigan, have invented a new and useful Tail-Light for Vehicles, of which the following is a specification.

This invention relates to signals adapted to be mounted on the rear ends of automobiles and other vehicles in order to indicate to any vehicles following the intention of the operator or driver of the vehicle thus equipped, and its object is to provide a tail light which shall be simple, easily operated and easily cleaned, and which can be constructed at low cost.

This invention consists in a shell having a longitudinal window in its rear side, of a series of properly perforated segmental shutters pivotally mounted in said shell and having means to swing them across the window, and an electric lamp within the shell.

It further consists in forming the shell with a window in the bottom and mounting a reflector adjacent thereto so that light from the lamp may be reflected onto a license tag or advertising sign so that it can be easily read by persons in the rear of the vehicle.

In the accompanying drawing Figure 1 is a rear elevation of this improved tail light. Fig. 2 is a section on the line 2—2 of Fig. 4. Fig. 3 is a front elevation of the device. Fig. 4 is a section on the line 4—4 of Fig. 1. Figs. 5 and 6 are elevations of a shutter.

Similar reference characters refer to like parts throughout the several views.

The ordinary tail lamps of automobiles and other vehicles merely indicate the presence of such vehicles, and automobiles often collide because the vehicle ahead turns to the right or left or even stops and reverses without notifying the vehicle following. The present device is so constructed that such notice can be given by a driver to everyone in position to see his tail lamp.

In the drawings, the shell 1, which may be cylindrical, has heads 2 and 3, a window 4 of transparent material, having a frame 5, a window 6 of similar material having a frame 7, and a door 8 mounted on a proper rod 9 carried by the eyes 10 of the shell to permit cleaning of the interior of the structure. The windows 4 and 6 may be of any

desired construction, either flat, curved, or in the form of lenses, but the window 4 is preferably of red glass and the window 6 of clear glass. Extending through hubs 12 on the heads 2 and 3, are screws 13 on which the shutters are mounted.

Four shutters are shown in Figs. 2 and 4, although the number may be changed as desired. Each has ends 14 and 15, an inwardly extending hub 16 on each end, an arm 17 on one of the ends, and a body 18 provided with an opening 19 so that the light from the lamp 20 can always shine through the glass 4. The body also has slots 21, forming characters, preferably constituting one of the words "Stop," "Reverse," "Left" and "Right." The shutters are arranged as shown in Figs. 2 and 4, with the hubs of one on the hubs of the adjacent shutter, and with the hubs of the inner shutter mounted on the inner ends of the screws 13. Each shutter has one arm 17 to which connects a wire or cord 24 that passes out of the shell through one of the holes 22 in the door. It is desirable that the arms 17 of adjacent shutters be at opposite ends of the shell so that the cords 24 may be separated. An electric cable 28, of any desired construction, connects to the lamp 20 mounted on the bracket 25, which bracket connects to the bracket 26, that supports the signal, by rivets 27.

The cords or wires 24 swing the shutters down against the pull of springs 28, one for each shutter, which springs connect to the shutters and to the eye-bolts 29 mounted on the door, thereby holding the front edges of the shutters against the bar 30 connected to the shell 1, and the upper edge of the door against this same bar. This pull of the springs prevents the shutters and the door from rattling. The springs 28 preferably connect to those ends 14 of the shutters to which the arms 17 are attached, and thus twisting of the shutters is avoided. The cords or wires 24 connect to any desired actuating mechanism. Thus, the cord from the "stop" shutter may connect to the clutch lever, the cord to the "reverse" shutter may connect to the reverse lever, while the cords to the "right" and "left" shutters may connect to readily accessible special devices.

A license tag 32 or sign of any desired construction and bearing proper figures, letters or other characters, may be secured to

the bracket 26 by screws 33. A window 34 may be mounted in the frame 35 in the bottom of the shell so that light from the lamp 20 may fall on the polished surface 36 and 5 be reflected down onto the tag 32.

The details of construction and the proportions of the different parts of this device may all be changed by those skilled in the art without departing from the spirit 10 of my invention as set forth in the claims.

I claim.

1. The combination of a cylindrical shell, ends for the same, a bracket to support the shell, windows in the side of the shell, pivots mounted in the ends of the shell, a series 15 of segmental shutters mounted on said pivots concentric with each other and having slots in the form of characters, a flexible actuating member for each shutter 20 adapted to move it across a window in the side of the shell, a lamp within the shell, a door formed in the shell to give access to

its interior, and springs connecting to the door and shutters to return the shutters and hold the door in position.

2. The combination of a cylindrical shell, 25 ends for the same, means to support the shell, a window in the side of the shell, pivots mounted in the ends of the shell, a segmental shutter mounted on said pivot and 30 having slots in the form of characters, a flexible actuating member for the shutter adapted to move it across the window, a lamp within the shell, a door formed in the shell to give access to its interior, and means 35 connecting the door and shutter to return the shutter and hold the door in position.

In testimony whereof I have signed this specification in the presence of two subscribing witnesses.

ERNEST E. SWEET.
